CLAIM

The ornamental design for an upholstered ottoman, as
shown and described.

DESCRIPTION

FIG. 1 is a top perspective view of an upholstered ottoman
showing my new design;

FIG. 2 is a top plan view;

FIG. 3 is a bottom plan view;

FIG. 4 is a front elevational view, the rear view being
identical thereof; and,

FIG. 5 is a side elevational view thereof, the side opposite
being identical thereof.
